UNITED STATES PATENT OFFICE.

FRANK STEVENS AND FREDERICK SPICKER, OF ROUNDUP, MONTANA.

DRILLING-MACHINE.

1,077,649.

Specification of Letters Patent.

Patented Nov. 4, 1913.

Application filed January 6, 1913. Serial No. 740,499.

To all whom it may concern:

Be it known that we, FRANK STEVENS and FREDERICK SPICKER, citizens of the United States, residing at Roundup, in the county 5 of Musselshell and State of Montana, have invented certain new and useful Improvements in Drilling-Machines, of which the following is a specification.

The present invention relates to improvements in boring and drilling machines especially adapted for use in connection with 10 Artesian and oil wells of standard type.

The essential object of the invention is the provision of a machine for this purpose 15 which is more efficient in its operation, facile in its manipulation and control, and capable of easy and rapid adjustment of its operating parts while in actual use.

The invention consists in certain novel 20 features and combinations and arrangements of parts, especially in the movement of the boring or drilling tool, feeding the rope to which the tool is attached, and in the provision of an advantageously arranged 25 tension device in connection with the stroke of the tool.

In the accompanying drawings one example of the complete physical embodiment 30 of the invention is illustrated, constructed according to the best mode so far devised for the practical application of the principles.

Figure 1 is a side view of the machine complete. Fig. 2 is a detail, front view of 35 the upper or top portion of the tower of Fig. 1. Fig. 3 is a plan view of the principal operating parts of the machine, other parts being omitted for convenience of illustration. Fig. 4 is a sectional detail view 40 showing the operating parts of the invention. Fig. 5 is a transverse sectional view showing in elevation, the tension device used in connection with the stroke mechanism, or "beater" shaft. Fig. 6 illustrates 45 in detail section the device for adjusting the stroke of the tool, and shows its relation to the beater shaft. Fig. 7 is a transverse sectional view through the supporting frame, showing the beater shaft and its actuating parts. Fig. 8 is an enlarged sectional detail of the stroke adjusting device. 50 Fig. 9 is an enlarged sectional detail view of the rope feed device.

In the preferred embodiment of the invention the machinery is mounted upon a frame 1 provided with wheels 2 for conven-

ience in transportation, and the motor 3, shown in conventional form might well be used to propel the vehicle as well as drive the fly or drive wheel 4, to which it is connected by belt as indicated in dotted lines 5.

A tower 6 located at the front of the apparatus comprises a convenient ladder, and is braced and connected to the frame by the brackets 7 and brace 8. A pulley 9 is 60 journaled at the top of the tower over which the tool rope 10 is passed, and a guide loop 11 for the rope is attached at a convenient point below the pulley. A tool 12 of usual or standard type is attached in the ordinary manner at the end of the rope, or this tool may be a special tool fashioned particularly for use with this machine.

The rope 10 is fed from the drum 13 whose shaft 14 is journaled in the frame 1 and is 75 provided with a feed controlling device including the screw 15 that is actuated from the handle 16. In Fig. 3 this feed device is shown out of operation, but when in position for use the screw or worm 15 is in mesh 80 with the complementary gear wheel 17 on the drum shaft 14. In Fig. 9 a spring pressed detent 18 is illustrated (the spring is indicated in dotted lines 18') as pivoted at 19 in a bracket 20, and the bracket, which 85 is hollow or open, has passed therethrough the screw bar 21. The bar 21 in Fig. 9 is in the same position as in Fig. 3, i. e. inoperative and is so held by the detent. If it is desired to turn the drum 13 on its shaft, the 90 detent is released by a pull on the draw rod 22, and the screw bar is shifted laterally so that the worm engages the gear wheel 17; the draw rod is then released and the detent returns to position to lock the bar 95 against lateral movement; and the crank or handle 16 is turned. This movement rotates the worm, and through it, the gear wheel and drum, to wind or unwind the rope as the case may be. This movement of the 100 drum is accomplished manually by an operator standing at the front of the machinery, but it will be understood that the drum may also be power driven. The power drive of the drum is taken from the driving shaft 105 23 by means of the clutch 24 and gear wheels 25 and 25', the latter located on the drum shaft, and the clutch being operable through the forked handle 26 as usual. A brake 27 of the usual band type may be used in connection with the drum to control the drum when it is running free. It will be under-

stood that the fly or driving wheel is loose on its shaft and actuates the drum only when the clutch 24 is coupled. At the opposite side of the fly wheel on the driving shaft, a 5 second clutch 28 is located, and this is designed to bring the stroke or rope impact device into operative relationship with the driving wheel. The clutch 28 is keyed to the shaft which is provided with a crank 10 29 upon which the pulley 30 is journaled, bearings 31 being provided for the crank.

In Fig. 4 the position of the rope with relation to the drum and crank shaft is clearly shown. Here the rope is illustrated 15 as passing from the drum over a tension device, and a stroke adjusting device to the "beater." This tension device comprises a pair of rolls or rollers 32 and 33 rotatable on their respective shafts 34 and 35. The 20 shafts are supported in side plates 36 and 37 and the upper shaft 34 provides a suspension means for the plates about which the tension device may swing. Each side plate is provided with a lower extension to which 25 a spring actuated bar 38 is pivoted at 39, the bar being passed through a bracket 40 and provided with a tension spring 41. A nut 42 is used to compress or permit the spring to expand when suitably operated.

30 The stroke adjusting device comprises a pulley wheel or roller 43 which is journaled in a carriage 44 provided with side flanges 45 that travel in grooves 46 in the side guide plates 47. The guide plates are suspended 35 from the frame 1, and the carriage has incased in its hollow head, the enlarged end 48 of the screw bar 49 which is threaded in the complementary block 50 attached to the frame 1. The screw bar 49 may be turned 40 by means of the handle or crank 51 to cause the carriage to move toward or away from the front of the machine.

In operation, the machinery is driven from

the motor and the proper clutch having been closed, the rope may be wound upon the 45 drum, as described. The drum clutch is then thrown out, and the clutch for the "beater" shaft is thrown into operation, after the boring tool has been placed in operative position. The function of the 50 "beater" as it revolves is to strike the rope 10 and thus lift the tool. The continued revolution of the crank permits the tool to fall thus making a stroke. As the boring proceeds, the drum may be revolved by hand 55 and the rope unwound to lower the tool as described. The slack is taken up at all times, and a tension is provided by the tension device.

The length of the stroke may be governed 60 and gaged by moving the stroke gage in or out, thus decreasing or increasing the stroke at will, as will be understood.

Having thus fully described our invention, what we claim is:—

1. In a boring machine, the combination with a drum, rope, and tool, of a rotary impact member carrying a pulley, a pivoted frame having a roller over which the rope passes between the drum and impact member, and a movable carriage having a pulley over which the rope passes between the frame and the impact member, whereby the stroke of the impact member may be varied.

2. In a boring machine, a stroke adjusting 75 device comprising a movable carriage and a pulley thereon, and a screw bar for actuating said carriage.

In testimony whereof we affix our signatures in presence of two witnesses.

FRANK STEVENS.
FRED. SPICKER.
